UNITED STATES PATENT OFFICE.

CHARLES F. GOODING, OF ORONOGO, MISSOURI.

BED-CLAMP.

958,246.

Specification of Letters Patent. Patented May 17, 1910.

Application filed March 15, 1910. Serial No. 549,381.

To all whom it may concern:

Be it known that I, CHARLES FRANKLIN GOODING, a citizen of the United States, residing at Oronogo, in the county of Jasper and State of Missouri, have invented certain new and useful Improvements in Bed-Clamps, of which the following is a specification.

This invention relates to bedsteads and particularly to a means for easily and expeditiously repairing a broken rail or bed leg, all as will be hereinafter more fully described and claimed, and illustrated in the accompanying drawings, in which—

15 Figure 1 is a side elevation of the clamp applied to a broken bedstead and Fig. 2 is a plan view of the same, the dotted lines indicating an open position of the clamp.

Throughout the following detailed description and on the several figures of the drawings, similar parts are referred to by like reference characters.

Referring to the drawings by reference characters, A indicates a broken casting or 25 lug formed on the bed leg B.

C indicates my improved clamp of peculiar form, including a substantially flat shank C', a pair of spaced parallel straps D, and a pair of straps E, hinged at F to the 30 straps D and at E' adapted to lie against the portions of the straps D which connect the same to the main portion of the clamp C.

G indicates the end of a bed rail adapted to be connected to the lug A under ordinary 35 conditions. The lugs being commonly made of cast iron are frequently broken, and thus disables the entire bedstead unless some means are provided to make a substantial repair. Again, the lugs are usually formed

upon the bed legs during the process of 40 manufacture, and hence are not readily replaceable.

In the event of a break of the character indicated the shank C' is bolted to the bed rail G by any suitable number of strong 45 bolts or screws H. The straps D are then caused to embrace the lug A, extending around the bed leg above and below said lug, the clamp members E at such time being free to swing on the hinges F. The next 50 step is to bring the members E around with their ends E' against the straps D, where they are secured by suitable fastening bolts K. The device may be cheaply made for the purpose set forth, of any suitable materials 55 or sizes to fit standard sizes of makes of bedsteads, and the same may be readily applied to a broken rail or leg by an ordinary mechanic, with the expenditure of little time and labor.

60 I claim:

The combination with a bed leg having a lug thereon and a rail adapted to be connected to said lug, of a clamp comprising a substantially flat shank, a pair of spaced 65 parallel straps embracing said lug and extending around the leg above and below said lug, auxiliary strap members hinged to the aforesaid straps and adapted to snugly embrace the bed leg, and means to secure the 70 straps and auxiliary strap members together, and means to secure said shank to the rail.

In testimony whereof I affix my signature in presence of two witnesses.

CHARLES F. GOODING.
